UNITED STATES PATENT OFFICE

PAUL H. OLSON, OF ST. PAUL, MINNESOTA

HEATING BOILER

Application filed February 10, 1927. Serial No. 167,165.

The present invention relates to a heating boiler.

In heating a liquid, the greater the surface of said liquid which is exposed to the heating means in proportion to its volume, the greater will be the transmission of heat to the liquid, other factors being equal.

An object of the present invention is to make a heating boiler having water compartments therein, and having passages therebetween for carrying heated gases upwardly about said compartments to heat fluid contained in said compartments.

Another object is to alternately superpose a plurality of double concave and double convex compartments in spaced relation, one above the other, said compartments being interconnected by passages which will permit a gradual flow of a heating fluid upwardly therethrough, and will also provide means for carrying sediment in said compartments downwardly therethrough.

In order to attain these objects, there is provided, in accordance with one feature of the invention, a heating boiler having a plurality of double concave compartments positioned one above the other, each with an opening centrally thereof; and having a double convex compartment of smaller diameter than said double concave compartments positioned centrally between each pair of superposed concave compartments.

These and other features of the invention, not specifically mentioned, will be more fully brought out in the following description and the accompanying drawings, wherein:

Figure 1, is a view partly in front elevation and partly in vertical section through a heating boiler embodying the features of the present invention;

Figure 2, is a view in top plan of a double convex water compartment; and

Figure 3 is a sectional view of a modified form of compartment.

Referring to the drawings in detail, a boiler A is shown of a type commonly employed in hot water heating plants where coal or oil is used as a fuel. The boiler is here shown as constructed of cast metal units, although the units may be made of sheet metal, if pre-

ferred, without departing from the spirit or scope of the invention.

The boiler A is provided with a grate 1 of a conventional type and is preferably provided with a water jacket 2 surrounding the fire pot above the grate. Extending inwardly from the upper portion of the water jacket surrounding the fire pot, and in open communication therewith, is a double concave portion 3 having an opening 4 centrally thereof to permit heated gases from the fire pot to ascend therethrough.

Spaced upwardly from the upper face of the double concave portion 3 and supported thereon by pipe connections which will be designated generally as B, is a double convex compartment 5 which may have a concave portion 6 in the center of the lower face thereof. The pipe connections B may be welded, or otherwise secured to the compartments, to make a water tight joint therewith. This concave portion is for the purpose of preventing sediment from settling on the bottom of the compartment 5, although it is not essential to the invention. The double convex compartment 5 is smaller in diameter than the double concave compartment 3, so as to be spaced inwardly from the outer wall of the boiler to permit heated gases to flow upwardly around the outer edge of said compartment 5.

Spaced upwardly from the double convex compartment 5 and supported as by means of other pipe connections B, is a double concave compartment 7. The outside diameter of the double concave compartment 7 is, in the present instance, somewhat smaller than the diameter of the lower concave compartment 3 so as to permit a pair of hinged casings 8 and 9, which, in the present construction, extend almost completely around the boiler to fit flush with the lower compartment, and an upper compartment to be later described. The double concave compartment 7 is spaced upwardly from the convex compartment 5 a distance substantially equal to that which separates the lower concave compartment and the double convex compartment 3.

Spaced upwardly from the double concave compartment 7 and supported as by means of

pipe connections B is a second double convex compartment 10. This compartment is also spaced upwardly from the double concave compartment 7 a distance substantially equal to the separation between the other compartments. Other double concave and double convex compartments may be alternately superposed, as required, in the manner shown, those illustrated being sufficient to fully disclose the invention.

A top compartment 11 having a lower concave surface is supported upon the upper double convex compartment 10 by means of pipe connections B and is provided with a central opening 12 which is connected to a stack, not shown, in a customary manner, to convey away the gases of combustion.

Threadedly inserted into the lower portion of the water jacket 2 is a pipe 13, while connected to the upper portion of the upper compartment 11 is a second pipe 14. Through the lower pipe 13 water may be supplied to the boiler, while the upper pipe conveys away the water, vapor, or steam heated by passing through the boiler. Various modifications to the boiler may be made, as by constructing it of sheet metal, and making it smaller in size for use in heating hot water storage boilers, etc. These and similar adaptions would occur to an ordinary mechanic, and are intended to be within the scope of the appended claims.

A fuel oil or gas burner is schematically indicated in dotted lines at 15 and may be substituted for coal as a fuel, if desired. The heated gases pass from the heating element upwardly through the central opening in the double concave compartment 8 into the upwardly sloping passage between the double concave compartment 8 and the double convex compartment 5. Here the gases are distributed radially outward over a large area of heating surface and as their cross sectional area increases their velocity is thereby greatly reduced. They pass upwardly around the outer edge of the double convex compartment 5 and then travel radially inward between the double convex compartment 5 and the next higher concave compartment 7. As they approach the center their speed of travel again increases, in accordance with a well known principle of aerodynamics, and as they reach the center they pass upwardly through the central opening of the double concave compartment 7. The process is repeated until the gases are finally passed to the stack at 12.

The fact that the gases are continuously traveling in an upwardly sloping passage prevents retarding of the draft, and the fact that the passages between the compartments are of substantially equal depth throughout eliminates eddy currents and dead areas with their attendant loss in heating efficiency.

The heat absorbing fluid within the boiler

has a free circulation upward from one compartment into the next, being introduced into each compartment near the lower portion of a heating surface thereof and being free for passage therefrom into the next higher compartment at a point near the lower portion of a heating surface thereof. For example, water from the lower compartment 8 passes from a point 16 near the center thereof upwardly through pipe B¹ into the lower portion of the double convex compartment 5 near the lower portion of a heating surface 17. The water is free to pass upwardly through the compartment 5 and thence through either connecting pipe B² near the outer edge of the double convex compartment 5, or through pipe B³ near the top thereof. Since the pipe B³ near the top is offset ninety degrees from the pipe B¹, through which, in the present instance the water is considered to have entered the compartment, the normal course of the water from the pipe B¹ is upwardly through the pipe B². This carries water over the heating surface 17.

Offset ninety degrees from the pipe B¹ is a pipe B⁴ also communicating between the lower double concave compartment 8 and the lower double convex compartment 5. Water entering the double convex compartment 5 through the pipe B⁴ finds a normal course of flow upwardly into the next higher double concave compartment through the pipe B⁵. This carries the water over the heating surface comprised in the upper face of compartment 5.

It will be further noted that since one pair of pipes is located near the bottom of each compartment, sediment is free to flow downwardly through the boiler to the lowermost point in the water jacket 2. From this point the sediment may be cleaned out at predetermined intervals, or, if desired, a small sediment space 18 may be left below the pipe 13, which would receive the sediment accumulation without interfering with the proper functioning of the boiler.

To facilitate proper circulation and eliminate any dead areas between the entrance point of a connecting pipe and either the top or the bottom of a compartment, said compartments may be formed with a bulge 20 (see Figure 3) on a level with the lowermost portion of said compartment. A similar bulge, inverted, may also be provided on a level with the uppermost portion of the compartments for each connecting pipe.

A pair of large cleanout doors 8 and 9 are here provided extending almost entirely around the boiler. By opening either of the doors, substantially half of the entire circumference of the compartments is exposed, and by inserting a brush between the compartments they may be cleaned thoroughly in a short space of time. Since the upper surface of the lowermost double concave compartment slopes inwardly, any accumulation of

ash or soot thereon would tend to flow inwardly on the downwardly sloping upper surface of this compartment and thereby prevent it from falling out upon the floor. This 5 construction greatly facilitates cleaning the boiler.

I claim:

A heating boiler, comprising a hollow lower water jacket having a top chamber having 10 horizontally arranged double concave walls and a narrow vertical annular chamber, the inner wall of which defines an enlarged fire chamber below, a compartment having double convex walls above said top chamber, nipples connecting said top chamber and compartment in superposed spaced relation and establishing communication therebetween, a second compartment arranged above the first compartment and having walls of double concave 15 configuration, nipples connecting the first and second compartments in spaced relation, a third compartment of double convex configuration above the second and connected thereto by nipples, a fourth compartment 20 above the third and connected thereto by nipples, the top chamber of the water jacket and the second and fourth compartments having central openings whereby communication between the spaces between the compartments 25 and the fire chamber is obtained and a casing surrounding the first, second, and third compartments and spaced from the first and third compartment and engaging said water jacket and the fourth compartment.

5 In testimony whereof I affix my signature.
